Primary Examiner — Ricky Pham(74) Attorney, Agent, or Firm — Ignite USA, LLC(57) CLAIM

The ornamental design for a "vent for food storage container," as shown and described.

DESCRIPTION

FIG. 1 is a perspective view of a vent for food storage container showing our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The subject matter shown in dashed lines is for illustrative purposes and forms no part of the claimed design.
